UNITED STATES PATENT OFFICE.

FRANK VICTOR, OF RIDGWAY, PENNSYLVANIA.

FLUSH DOOR.

Application filed March 26, 1928. Serial No. 264,903.

This invention relates to improvements in doors and more particularly to doors of the flush type. Doors of this type, as previously constructed, have presented various disadvantages. Some doors of this type have been made with a solid core with the result that they are expensive to manufacture due to the amount of material required, are undesirably heavy, and, are liable to warp under changes in weather conditions. The present invention therefore has as one of its objects to provide a door of the flush type which, while exceptionally substantial and durable and having a desired massive appearance, will, at the same time, be comparatively light in weight, inexpensive to manufacture, not subject to warping, and sound-proof.

Briefly described, the door, embodying the invention, comprises a frame structure which constitutes the body of the door and which consists of an inner or core frame and an outer or edging frame, in combination with panels which constitute the faces of the door and which are assembled with and permanently secured to the said body frames, and the invention has as a further object to so construct the frames comprising the body of the door that the component members of the frames may be readily assembled and will embody interlocking parts of an extremely simple nature which may be readily formed and interfitted so as to prevent any relative displacement of the component parts of the core and edging frames when assembled, the invention likewise contemplating, in this connection, the formation and construction of the interlocking parts of the frame members so that not only will members of each frame be mutually locked together, but likewise the members of the two frames will be mutually locked together, so that the door, as a whole, will be exceptionally substantial and there will be no tendency toward separation of any of its component parts either due to slamming of the door or to expansion and contraction or changes in weather conditions.

Another object of the invention is to so construct the body frame structure of the door and the panels of the door that a firm, substantial and yet simple interlocking of the panels and frame may be effected thereby providing against any likelihood of separation of the panels from the frame and also providing against any distortion of the panels due to warping.

Another object of the invention is to provide a door of the flush type, which while substantial and durable, may have the major areas of its panels spaced with respect to each other to provide dead air spaces within the door to render the same substantially sound-proof.

While the accompanying drawings and the description which is to follow, constitute a disclosure of the preferred embodiment of the invention, it will be understood the various changes may be made within the scope of what is claimed.

In the accompanying drawings:

Figure 1 is a view in elevation of a door constructed in accordance with the present invention, a portion of the panel at the near side of the door being broken away to illustrate a portion of the body frame structure in elevation:

Figure 2 is an edge elevation of the door;

Figure 3 is a top plan view of the door;

Figure 4 is a detail vertical sectional view taken substantially on the line 4-4 of Figure 1;

Figure 5 is a horizontal sectional view taken substantially on the line 5-5 of Figure 1;

Figure 6 is a fragmentary, sectional, group perspective view illustrating the body frame members of the door and one of the panels, mutually separated;

Figure 7 is a view partly in elevation and partly in vertical section illustrating one lower corner of the body frame structure of the door, one of the stiles of the edging frame being omitted for the sake of clearness;

Figure 8 is a view in side elevation of the structure shown in Figure 7;

Figure 9 is a vertical transverse sectional view taken substantially on the line 9-9 of Figure 7 looking in the direction indicated by the arrows;

Figure 10 is a plan view of the structure shown in Figure 7;

Figure 11 is a fragmentary sectional perspective view of one lower corner of the body frame structure of the door, the parts being assembled and interlocked;

Figure 12 is a horizontal sectional view

taken substantially on the line 12—12 of Figure 11 looking in the direction indicated by the arrows;

5 Figure 13 is a detail horizontal sectional view taken substantially on the line 13—13 of Figure 1 looking in the direction indicated by the arrows;

10 Figure 14 is a fragmentary sectional perspective view of one lower corner of the door structure as a whole, parts being broken away and some parts omitted.

15 The door, embodying the invention, comprises a body frame structure including a core frame and an edging frame, in combination with panels, and in the drawings the core frame is indicated in general by the numeral 1, the edging frame by the numeral 2, and the panels by the numeral 3. The core frame 1 comprises stiles 4, top and bottom rails 5, and intermediate rails 6, all of these rails being preferably of the same cross sectional dimensions and each being formed in its opposite longitudinal edges with longitudinally medially extending dovetail grooves, the grooves in the inner edges of the stiles 4 being indicated by the numeral 7 and those in the outer edges of the stiles by the numeral 8, and the grooves in the upper and lower edges of the top and bottom rails 5 being indicated by the numeral 9. These particularly referred to grooves in the stiles and rails of the core frame serve a useful purpose, in the structure, as will presently be made clear, and 20 while the lower and upper edges of the top and bottom rails 5 are formed with similar grooves as are also the upper and lower edges of the intermediate rails 6, these grooves serve no useful purpose and are merely present due to the fact that all of the members of the frame are, as stated, of the same cross sectional dimensions and contour and therefore may all be cut from the same stock, thus effecting a great saving in 25 material as well as labor incident to the production of the several frame members. By reference to Figures 6, 12 and 13 of the drawings, it will be observed that the ends of the rails 5 and 6 are formed with tenons 30 which fit into the grooves 7 in the inner edges of the stiles 4 of the core frame and as these tenons are of dovetail form, the engagement of the same in the dovetail grooves 7 serves to provide an interlocking connection between the members of the said core frame, this frame, when set up, being of 35 rectangular form.

40 The edging frame likewise comprises stiles which are indicated by the numeral 11, and top and bottom rails indicated by the numeral 12, and by reference to Figures 3, 5, 6, 11, 12, and 13, it will be observed that each stile 11 is formed upon its inner face or edge with a longitudinally extending dovetail rib 13, these ribs being slidably

fitted into the grooves 8 of the stiles 4 of the door frame as shown in Figures 5, 11, 12 and 13 whereby the stiles of the edging frame are interlocked throughout their length with the corresponding stiles of the core frame. For a purpose to be presently explained, each stile 11 is further formed in its inner face at opposite sides of the dovetail rib 13, with a relatively narrow and deep groove 14, these grooves extending 45 parallel with respect to the rib 13 and likewise parallel to the vertical side edges of the respective stile and relatively close to said side edges. In a like manner, the top and bottom rails of the edging frame are similarly formed, these rails being provided upon their under and upper faces, respectively, each with a longitudinally extending dovetail rib 15 and these ribs fitted at their ends into dovetail grooves 16 which are formed at 50 the upper and lower ends of the stiles 4 of the core frame, the said dovetail ribs 15 fitting in the dovetail grooves 9 in the upper and lower sides of the top and bottom rails 5 of the core frame, it being understood 55 at this point that after the members of the core frame have been assembled and interlocked, the rails 12 of the edging frame are assembled with the core frame by being slid into the interlocking engagement therewith which is effected by the fitting of the said ribs 15 in the grooves 9 and 16. In this manner the top and bottom rails 12 of the edging frame are interlocked with the corresponding rails as well as the stiles of the core frame. By reference to Figure 7, it will be observed at this point, that the ends of the top and bottom rails 5 of the core frame abut against the inner edges of the stiles 4 of said frame at the upper and lower 60 ends thereof and it will likewise be observed by reference to Figure 7 that the ends of the ribs 15 upon the top and bottom rails of the edging frame terminate flush with the inner walls of the dovetail grooves 8 65 which, as previously stated, are formed in the outer edges of the said stiles 4 of the core frame. As shown in Figure 6 of the drawings, each rail 12 of the edging frame is formed at each end with a vertically disposed dovetail groove 17 and it will be observed by reference to Figure 3 of the drawings that the ends of the dovetail ribs 13 upon the inner faces of the stiles 11 of the edging frame fit in these grooves thus providing an interlocking engagement between the rails and stiles. As illustrated in Figures 3, 6, 7, 8 and 14 of the drawings the top and bottom rails 12 of the edging frame are formed in their upper and under sides with longitudinally extending relatively narrow and deep grooves 18 which are parallel to the ribs 15 of the respective rails and to the outer edges thereof and which are located relatively close to the said outer 70 75 80 85 90 95 100 105 110 115 120 125 130

edges, these grooves corresponding to the grooves 14 formed in the stiles 11 of the said edging frame and matching at their ends with the respective ends of respective ones of the grooves in the stiles. It will also be observed by reference to Figures 6, 8 and 14 of the drawings that each rail 12 of the edging frame is formed at each end, in a vertical plane with a respective one of 10 the grooves 18, with a tongue 19 which is of a thickness equal to the width of the respective groove. The purpose of these tongues will presently be explained.

From the description of the invention, thus far given, and by reference to the drawings, it will now be evident that when the component members of the core frame are assembled by sliding the dovetail tenons 10, upon the top and bottom rails 5 of said 20 frame, into the upper and lower ends of the dovetail grooves 7 in the stiles 4, the rails and stiles will be interlocked so that there can be no lateral separation of the stiles from the rails. It will likewise be evident that 25 when the top and bottom rails 12 of the edging frame are assembled with the upper and lower ends of the core frame by slidably engaging the dovetail ribs 15 in the dovetail grooves 9 and 16 in the rails 5 and stiles 4 respectively, of the core frame, there is effected 30 an interlocking of the top and bottom rails of the edging frame with the upper and lower ends of the core frame and likewise a locking of the top and bottom rails 5 of the 35 core frame against vertical longitudinal displacement between the stiles of said frame. It will also be evident from the foregoing that when the stiles 11 of the edging frame are assembled with the stiles 4 of the core 40 frame and with the ends of the rails 12 of the edging frame by a slidable engagement of the tongues 13 of the stiles 11 in the dovetail grooves 8 of the stiles 4 of the core 45 frame, there will be not only an interlocking of the stiles of the edging frame with the stiles of the core frame, but likewise a locking of the ends of the top and bottom rails 5 and 15 of the core and edging frames with the stiles 11 of the edging frame and, when 50 all of the frame sections are assembled in the manner stated, there can be no relative separation or displacement of any of the sections except when one or the other of the stiles 11 of the edging frame is removed, so 55 that, when the frame members are assembled, as stated, and these two stiles are in place, there is produced an exceptionally substantial and durable frame structure the parts of which are so interlocked as to preclude any 60 relative displacement or disarrangement thereof.

The two panels 3 are of identical construction and each of these panels is preferably of three-ply structure, comprising outer and 65 inner plies indicated respectively by the nu-

merals 20 and 21, and an intermediate ply 22. These plies are facially united to one another by adhesive and the plies 20 and 21 are so arranged that the grain thereof will extend in the same direction and preferably vertically of the panel or in other words vertically of the door in its entirety. The grain of the intermediate ply 22 runs at right angles to the grain of the plies 20 and 21 or in other words transversely of the panel or door and, 70 in this manner, warping of the panel plies is effectually prevented.

By reference to Figures 4, 5 and 6 of the drawings it will be observed that the outer plies 20 of each panel is of greater marginal 80 dimensions than the inner plies 21 and that the intermediate plies 22 is of less dimensions than the plies 21, so that the plies 20 projects marginally beyond the plies 21 and the plies 22 is marginally spaced inwardly with respect 85 to the plies 20 and 21 thus providing, in the panel, as a whole, projecting marginal portions 23 and 24, upon the plies 20 and 21 respectively. The panels are assembled with the body frame structure of the door after 90 the component parts of the core frame and the edging frame have been assembled, with the exception of one of the stiles 11 of the edging frame. The panels are slidably fitted to the frame structure with the upper and 95 lower projecting marginal portions 23 of the plies 20 of each panel slidably contacting the outer faces of the rails of the edging frame and the upper and lower projecting marginal portions of the plies 21 of each panel slidably 100 fitting in the grooves 18 in the upper and lower rails of the said edging frame, and after the panels have been thus assembled with the frame structure, the frame stile 11, above specifically referred to, is slidably ad- 105 justed into place. This completes the door structure, and in order that all of the assembled parts may be mutually united, it is preferable that an adhesive coating be applied to the contacting surfaces of the component 110 parts of the structure, where they interfit or interlock. It will be observed by reference to Figure 14 of the drawings that when the panels are assembled with the frame structure of the door, the lower corners of the 115 plies 21 of the panels will register with the upper edges of the projecting lug portions 19 of the top and bottom rails 12 of the edging frame, these tongues therefore projecting into the grooves 14 formed in the stiles 11 of 120 the edging frame.

From the foregoing description of the invention it will be evident that a door, constructed in accordance with the invention, may be manufactured at a great economy in 125 material and labor and in less time than the ordinary constructions of doors of this type. It will furthermore be evident that due to the peculiar arrangement of the component members of the core and edging frames and 130

the peculiar manner in which these frames are interlocked and mutually connected, both as regards their component members and likewise with respect to each other, an exceptionally strong and durable frame structure is provided to constitute the body of the door, and as this structure is of open frame-like form, the door will be hollow and therefore substantially sound-proof. At the same time the door is sufficiently substantial and durable to effectually serve its purpose and at the same time is not subject to warping or any other distortion due either to shock or to changes in weather conditions.

15 It will be evident from the foregoing description of the invention that the core frame 1 is of greater mass than the edging frame 2 and constitutes, in effect, the body of the door, the panels 3 providing finished faces for the door, and the edging frame constituting not only a finished edging for the door as a whole, but likewise, coacting with the core frame and panels to enhance the rigidity and durability of the structure as 25 a whole.

It will be understood of course that the door, embodying the invention, may be constructed of wood, metal, a composition of material, or any combination of different 30 materials.

Having thus described the invention, what I claim is:

1. In a door of the class described, a core frame, an edging frame, the said frames each comprising members having interlocking parts for holding the same assembled to form the respective frame, and certain of the members of the two frames having interlocking parts for holding the frames mutually assembled, and panels extending over the opposite sides of the assembled frames and having interlocking engagement with one of said frames.

2. In a door of the class described, a core frame, an edging frame, the said frames each comprising members having interlocking parts for holding the same assembled to form the respective frame, and certain of the members of the two frames having interlocking parts for holding the frames mutually assembled, and panels extending over the opposite sides of the assembled frames and having interlocking connection with the edging frame.

3. In a door of the class described, a core frame, an edging frame, the edging frame being assembled about the core frame, the said frames each comprising members having interlocking parts for holding the same assembled to form the respective frame, and corresponding members of the two frames having mutually interlocking parts for holding the frames mutually assembled, and panels extending over the opposite sides of the assembled frames and having interlock-

ing engagement with the members of the edging frame.

4. In a door of the class described, a core frame comprising frame members having interlocking parts for holding the members assembled to form the said frame, an edging frame including members corresponding to the members of the core frame and assembled about the core frame, corresponding members of the core and edging frames having interfitting rib and groove connection with each other whereby to maintain the frames mutually assembled, and panels extending over the opposite sides of the assembled frames, and having marginal interlocking engagement with the members of the edging frame.

5. In a door of the class described, a core frame, an edging frame, the said frames each comprising members having interlocking parts for holding the same assembled to form the respective frame, and certain of the members of the two frames having interlocking parts for holding the frames mutually assembled, the members of the edging frame having grooves in their inner sides extending parallel to their outer faces, and panels extending over the opposite sides of the assembled frames and of multiply construction and having projecting edge portions of one ply fitting into interlocking engagement in the said grooves of the edging frame whereby to mutually interlock the panels and the members of the edging frame.

6. In a door of the class described, a core frame, an edging frame, the said frames each comprising members having interlocking parts for holding the same assembled to form the respective frame, the edging frame being assembled about the core frame, certain of the members of the two frames having interlocking parts for holding the frames mutually assembled, the members of the core frame being of a width less than the corresponding members of the edging frame, the members of the edging frame being provided in their inner sides with longitudinally extending grooves, the grooves being located in the portions of the members of the edging frame which project beyond the side faces of the corresponding members of the core frame, and a multiply panel extending over each side of the assembled frame structure, each panel having its outermost ply provided with projecting marginal portions extending over the outer faces of the members of the edging frame and another of the plies of the panel having projecting marginal portions seating in the grooves in the members of the said edging frame.

7. In a door of the class described, a core frame comprising stiles and top and bottom rails, the stiles having dovetail grooves in their inner and outer sides, the said rails having grooves in their upper and under sides

respectively and being provided at their ends with tenons fitting in the grooves in the inner sides of the stiles, whereby the members of the core frame are mutually interlocked 5 and held in assembled relation, an edging frame surrounding the core frame and comprising stiles having dovetail ribs upon their inner sides interfitting in the dovetail grooves in the outer sides of the stiles of the 10 core frame, the said edging frame further comprising upper and lower rails provided upon their upper and under sides respectively with dovetail ribs having interfitting engagement in the grooves in the upper and 15 under sides of the top and bottom rails of the core frame, the ends of the rails of the edging frame being provided with dovetail notches to accommodate the respective ends 20 of the dovetail ribs of the stiles of said edging frame, and panels extending over the opposite sides of the assembled frames.

8. In a door of the class described, a core frame comprising stiles and top and bottom rails, the stiles having dovetail grooves 25 in their inner and outer sides, the said rails having grooves in their upper and under sides respectively and being provided at their ends with tenons fitting in the grooves in the inner sides of the stiles, whereby the 30 members of the core frame are mutually interlocked and held in assembled relation, an edging frame surrounding the core frame and comprising stiles having dovetail ribs upon their inner sides interfitting 35 in the dovetail grooves in the outer sides of the stiles of the core frame, the said edging frame further comprising upper and lower rails provided upon their upper and under sides respectively with dovetail ribs having 40 interfitting engagement in the grooves in the upper and under sides of the top and bottom rails of the core frame, the ends of the rails of the edging frame being provided with dovetail notches to accommodate the respective ends 45 of the dovetail ribs of the stiles of said edging frame, and panels extending over the opposite sides of the assembled frames, the stiles and rails of the edging frame having longitudinally extending grooves in their inner sides, and 50 said panels being of multiply structure and having projecting marginal ply portions having interfitting engagement in said grooves, each panel having projecting marginal portions of its outermost ply extending over the outer faces of the stiles and rails of the edging frame at the corresponding side of the frame structure.

10. In a door of the class described, a core frame, an edging frame, the said frames each comprising members having interlocking parts for holding the same assembled to form the respective frame, certain of the members of the two frames having interlocking parts for holding the frames mutually assembled, the members of the edging frame being provided in their inner sides with longitudinally extending grooves, the members of the core frame being of less width than the corresponding members of the edging frame and said 55 grooves in the members of the edging frame being located in planes beside the faces of the members of the core frame, opposite ones of the members of the edging frame having projecting tongues located in the planes of the grooves, and panels extending over the opposite sides of the assembled frames, the panels being of multiply form, the margins of the outer plies extending over the outer faces of the members of the edging frame and the margins of an inner 60 one of the plies of each panel fitting in the grooves in the members of the edging frame, the said lugs at the said ends of the said opposite members of the edging frame constituting continuations of the opposite marginal portions of the last mentioned plies of the panels.

55. 9. In a door of the class described, a core frame comprising stiles and top and bottom rails, the stiles having dovetail grooves in their inner and outer sides, the said rails having grooves in their upper and under sides respectively and being provided at their ends with tenons fitting in the grooves in the inner sides of the stiles, whereby the members of the core frame are mutually interlocked and held in assembled relation, an 65 edging frame surrounding the core frame

and comprising the stiles having dovetail ribs upon their inner sides interfitting in the dovetail grooves in the outer sides of the stiles of the core frame, the said edging frame further comprising upper and lower 70 rails provided upon their upper and under sides respectively with dovetail ribs having interfitting engagement in the grooves in the upper and under sides of the top and bottom rails of the core frame, the ends of the rails of the edging frame being provided with dovetail notches to accommodate the respective ends of the dovetail ribs of the stiles of said edging frame, and panels extending over the opposite sides of the assembled frames, the stiles and rails of the edging frame having longitudinally extending grooves in their inner sides, and said panels being of multiply structure and having projecting marginal ply portions 75 having interfitting engagement in said grooves, each panel having projecting marginal portions of its outermost ply extending over the outer faces of the stiles and rails of the edging frame at the corresponding side of the frame structure.

10. In a door of the class described, a core frame, an edging frame, the said frames each comprising members having interlocking parts for holding the same assembled to form the respective frame, certain of the members of the two frames having interlocking parts for holding the frames mutually assembled, the members of the edging frame being provided in their inner sides with longitudinally extending grooves, the members of the core frame being of less width than the corresponding members of the edging frame and said 100 grooves in the members of the edging frame being located in planes beside the faces of the members of the core frame, opposite ones of the members of the edging frame having projecting tongues located in the planes of the grooves, and panels extending over the opposite sides of the assembled frames, the panels being of multiply form, the margins of the outer plies extending over the outer faces of the members of the edging frame and the margins of an inner 105 one of the plies of each panel fitting in the grooves in the members of the edging frame, the said lugs at the said ends of the said opposite members of the edging frame constituting continuations of the opposite marginal portions of the last mentioned plies of the panels.

11. In a door of the class described, a core frame comprising stiles and top, intermediate and bottom rails, the stiles having dovetail grooves in their inner and outer sides, the top and bottom rails having grooves in their upper and under sides respectively and all of the rails being provided at their ends with tenons fitting in 110

the grooves in the inner sides of the stiles, whereby the members of the core frame are mutually interlocked and held in assembled relation, an edging frame surrounding the core frame and comprising stiles having dovetail ribs upon their inner sides interfitting in the dovetail grooves in the outer sides of the stiles of the core frame, the said edging frame further comprising upper and lower rails provided upon their upper and under sides respectively with dovetail ribs having interfitting engagement in the

grooves in the upper and under sides of the top and bottom rails of the core frame, the ends of the rails of the edging frame being provided with dovetail notches to accommodate the respective ends of the dovetail ribs of the stiles of said edging frame, and panels extending over the opposite sides of the assembled frames. 15

In testimony whereof I affix my signature. 20

FRANK VICTOR.
